(57) **CLAIM**

The ornamental design for a woofer, as shown and described.

DESCRIPTION

FIG. 1 is a perspective view showing the top, left side and front of a woofer which forms a first embodiment of my design;

FIG. 2 is a top plan view thereof;

FIG. 3 is a bottom plan view thereof;

FIG. 4 is a left side elevational view thereof;

FIG. 5 is a right elevational view thereof;

FIG. 6 is a front elevational view thereof;

FIG. 7 is a rear elevational view thereof;

FIG. 8 is a perspective view showing the top, left side and front of a woofer which forms an alternate embodiment of my design; and,

FIG. 9 is a front elevational view thereof; the top and bottom plan views, the left and right side elevational views, and the rear elevational view thereof being identical to the views shown in FIGS. 2, 3, 4, 5 and 7 respectively.
